UNITED STATES PATENT OFFICE.

ARTHUR G. THOMPSON, OF NEW YORK, N. Y., ASSIGNEE TO A. KIMBALL COMPANY, OF NEW YORK, N. Y., A CORPORATION OF NEW YORK.

PIN-TICKET.

1,252,862.

Specification of Letters Patent.

Patented Jan. 8, 1913.

Application filed April 7, 1913. Serial No. 759,280.

To all whom it may concern:

Be it known that I, ARTHUR G. THOMPSON, a citizen of the United States, residing at New York, county of New York, State 5 of New York, have invented an Improvement in Pin-Tickets, of which the following description, in connection with the accompanying drawing, is a specification, like characters on the drawing representing like 10 parts.

This invention relates to pin tickets designed for attachment to cloth, garments, or other articles, to serve as the indication of price, style, or for other purposes as such 15 devices are or may be used.

The object of the invention is to provide a device of this character in which the penetrating and attaching member shall be incapable either of injuring the person attaching 20 it to the cloth, garment, or other article, or of injuring the cloth, garment, or other article itself. When the penetrating points of the penetrating and attaching member consist of sharpened pins or wire, these 25 points are liable, when carelessly handled, or through accident, to injure the hands of the user. Furthermore, owing to the fact that devices of this character must be made extremely cheaply and consequently cannot 30 be carefully finished, there is often a bur, roughness, or sharp edge on the penetrating member which cuts the threads or fibers of garments or fabrics to which it is attached or catches upon and draws out the fine fibers, 35 thereof, thus injuring or disfiguring the article.

This invention obviates any such disadvantages and presents a pin ticket in which the penetrating and attaching pins are 40 smooth surfaced throughout and present smooth, rounded points while still readily penetrating the cloth, garments, or articles to which the ticket is to be attached.

The nature of the invention will appear 45 more fully from the accompanying description and drawings and will be particularly pointed out in the appended claims.

The drawings show a preferred form of pin ticket embodying the invention.

50 In the drawings:—

Figure 1 is a perspective view of the pin ticket looking at the rear side thereof.

Fig. 2 is a perspective view of the penetrating and attaching member.

55 The pin ticket is composed of the card

1 which may be of any desired or usual size, shape, and material, and which is adapted to bear upon its front face the usual or any desired indicia, such as of price or style.

The penetrating and attaching member is 60 shown separate from the card in Fig. 2 and is formed from a single piece of wire which by reason of the principle of this invention may be of considerably smaller diameter than that which otherwise would be used. 65 Both ends of the wire are doubled back upon the wire itself to present the double penetrating pins 2 and 3 thus securing smooth rounded points 4 and 5 on the pins.

Holes 6 and 7 are provided in the card 70 near one edge thereof through which the wire of the penetrating and attaching member is passed. In the form illustrated, that portion of the wire constituting the penetrating pins 2 and 3 is passed through these 75 holes and in any case the penetrating pins project from the rear face of the card in a substantial parallel relation as shown in Fig. 1.

The central portion of the wire is bent 80 about the edge of the card and clamps the card between its bends so as securely to hold the penetrating and attaching member in place. In the construction illustrated the double portion of the wire extends at 8 and 85 9 from the holes 6 and 7 along the front face of the card to and about the adjacent edge, the free ends 11 and 12 being bent back upon the rear face of the card and the intermediate central portion 13 being bent back in 90 loop form against the rear face of the card.

It will thus be seen that the penetrating and attaching member is firmly secured to the card both by being passed through holes in the card and by being bent about and 95 clamped to the edge of the card. It will also be seen that the penetrating pins 2 and 3 project from the rear face of the card and the wire in these penetrating pin portions is double and continuous throughout to present 100 smooth surfaces and smooth rounded points.

The pin ticket is attached to the cloth, garment, or other article in the usual manner, the penetrating pins being pushed through the fabric or article without danger 105 of injury to the hands of the user, without danger of catching or cutting threads or fibers, and without danger of catching and pulling out any fine fibers. When the pins are thus passed through, they are bent back 110

against the rear face of the card thus securing the card in place.

Having fully described my invention, what I claim as new and desire to secure by Letters Patent is:

1. A pin ticket comprising a card and a penetrating and attaching member constituted of a single piece of wire passed through and clamped by bends therein to said card and presenting a pair of pins projecting from one side of the card, the wire in the pin portions being continuous and doubled to present smooth, rounded, penetrating points.
2. A pin ticket comprising a card provided with a pair of holes near its edge, a wire having its ends doubled back upon itself to present a pair of double penetrating pins with smooth rounded points, the said pins projecting through said holes, and the central portion of said wire extending from said holes to and about said edge and clamped to the card.
3. A pin ticket comprising a card provided with a pair of holes near its edge, a wire having its ends doubled back upon itself to present a pair of double penetrating pins with smooth rounded points, the said pins projecting through said holes, and the free ends of said wire and the central portion of said wire extending from said holes to and about said edge and clamped to the card.
4. A pin ticket comprising a card, a wire having its ends doubled back upon itself to present a pair of double penetrating pins with smooth rounded points, the said pins projecting from one side of the card near the edge to a predetermined extent and in substantial parallelism, and the central por-

tion of the wire bent about the edge of the card, passed through, and clamped to said card.

5. A pin ticket comprising a card, a penetrating and attaching member constituted of a single piece of wire passed through said card and presenting a pair of pins projecting from one side of the card, the wire in the pin portions being continuous and doubled to present smooth rounded penetrating points, the free ends of the wire lying against the face of the card through which the pins project and the central portion of the wire bent about the edge of and clamped to said card.

6. In a pin ticket having a plurality of round-pointed double-shank pins formed of a single piece of wire, the wire between said pins engaging with the ticket to form a support therefor, the shank of said pins passing through the ticket and the free ends of the wire being bent to engage with both surfaces of the ticket to hold the pins in engagement therewith.

7. In a pin-ticket having a plurality of round-pointed double-shank pins formed of a single piece of wire, the wire between said pins being bent so as to engage with the upper and under sides of the ticket, the shanks of said pins passing through the ticket and the free ends of said wire engaging with both sides of the ticket to hold the pins in connection therewith.

In testimony whereof, I have signed my name to this specification, in the presence of two subscribing witnesses.

ARTHUR G. THOMPSON.
